UNITED STATES PATENT OFFICE

2,417,509

AUTOMATIC WELT TURNING APPARATUS

William Gordon Macdonald and William Arthur Cooper, Loughborough, England, assignors to William Cotton Limited, Loughborough, England

Application February 14, 1944, Serial No. 522,328
In Great Britain July 9, 1943

3 Claims. (Cl. 66—96)

1

This invention concerns Cotton's patent and other straight bar knitting machines equipped with automatic welt-turning apparatus. As is well known in such machines the welt-turning apparatus consists of a welt bar equipped with instruments which engage an initial course of the welt and draw the welt fabric away from the needles to a predetermined extent. A welt rod is then inserted and is connected by straps to a beam roller which is biased by a weight to turn in such a direction as will cause the fabric to be drawn off by the welt rod. The welt bar is then advanced to the needles to restore the initial welt course to them.

According to the present invention in a Cotton's patent or other straight bar knitting machine of the type equipped with automatic welt-turning apparatus including a welt bar movable away from the needles during the production of at least a part of the welt fabric and towards the needles to restore the welt to them, and with biased draw-off apparatus for connection to a welt rod, there is provided mechanism for relaxing the pull of the said apparatus during the said advance of the welt bar. In a machine wherein the draw-off apparatus comprising a shaft or other rotary member biased to rotate in a draw-off direction there may be a coupling which idles during said draw-off rotation and mechanism for operating said coupling to rotate said member in the reverse direction at the required time. This coupling may comprise a ratchet wheel for transmitting said reverse rotation to the shaft or other rotary member, a pawl carrier rotatable about the axis of the ratchet wheel, a pawl on the carrier, a device for holding the pawl out of engagement with the ratchet wheel, and means for moving it into engagement upon rotation of the carrier.

The foregoing and other features of the invention are incorporated in the construction which will now be described, as an example of the application of the invention to a Cotton's patent knitting machine having automatic welt-turning apparatus, with reference to the accompanying drawings in which

Figure 1 is a sectional view taken in a vertical plane at right angles to the length of the machine adjacent to the right hand end thereof on the line A—A in Fig. 3;

Fig. 2 is a sectional elevation, on a larger scale, taken on the line A—A in Fig. 3, showing certain parts of the mechanism;

Fig. 3 is a front elevation of the parts shown in Fig. 2.

2

In Figure 1, only those parts are shown that are relevant to the present invention, including a welt bar 10 movable horizontally towards and away from the needles 11. The machine also has a beam roller 12 mounted on a beam roller shaft 13 rotatable in bearings such as 40 and carrying straps 14 which may be attached to a welt rod 15 placed, manually or automatically, on the top of the welt fabric F at the appropriate stage in its production so that by rotation by the beam shaft 13 a bight of the welt fabric is drawn beneath the welt bar 10, the latter being then advanced towards the needles 11 to restore the initial welt course to them. It will be understood that in the case of a multi division machine there is a welt bar and a beam roller to each division, said rollers being mounted on a common shaft. The foregoing apparatus is well understood in the art and needs no further illustration or description.

The beam shaft 13 is biased to rotate in a draw-off direction, preferably by a weight 16 which operates through a pulley 17, in known manner, these parts, and the strap 14, are shown in chain dotted lines in Figs. 1 and 2 because they lie to the left of line A—A, Fig. 3; and the desirability of removing the draw-off tension from the fabric during the aforesaid advance of the welt bar 10 will therefore be appreciated. To effect this tension release a pawl and ratchet mechanism (indicated generally by the numeral 18 in Fig. 1 and shown in more detail in Figs. 2 and 3) is mounted on the beam shaft. This mechanism comprises a ratchet wheel 19 secured to the said shaft 13 to rotate it in the reverse direction, a pawl carrier 20 rotatable about the shaft but stationary during draw-off rotation of roller 12, and a pawl 21 on the carrier for engagement with the ratchet wheel 19. This pawl 21 is normally held out of engagement with the wheel 19, but is only moved into driving engagement when the said reverse rotation is applied to the carrier 20. For this purpose a stationary bluff 22 is provided which, in one attitude of the carrier 20, bluffs the pawl 21. The latter has a projection 23 which is engaged beneath a chain or the like flexible connection 24 that has one end secured to the carrier 20 at 25; said chain 24 is wrapped round the carrier 20 and has its other end secured at 26 to a truck lever 27 hereinafter mentioned. When the chain 24 is pulled the carrier 20 is rotated to move the pawl 21 off the bluff 22 and at the same time the chain 24 tightens over the projection 23 and the pawl moves inwards, as soon as the bluff permits, into en-

gagement with the ratchet wheel 19 so that the latter is rotated to apply the necessary reverse rotation to the beam shaft 13. At the extremity of this rotary movement the pawl 21 may, if desired, again engage the bluff 22 so as to be disengaged from the ratchet wheel. The carrier 20 is thereupon returned and the chain 24 wound up by means of a return spring 24a. If desired, the pawl may be urged out of engagement with the ratchet wheel by means of a spring which is overcome by the constrictive pressure of the chain on the aforesaid projection. The bluff 22 may be adjustable about the axis of the carrier 20 so as to provide an adjustment for the timing of the reverse rotation, suitable adjustment means being indicated at 37.

The chain 24 is pulled by means of a horizontal truck lever 27 pivoted at one end 28 to a suitable part 29 of the machine frame, and carrying a truck 30 adapted to engage a cam 31 on a shaft 32 which extends parallel to and is connected to rotate at the same speed as the main shaft 33, the driving connections being indicated at 34. In order that the pull may be applied to the chain 24 at the appropriate phase in the knitting operations, the said truck 30 is shogged into and out of engagement with the cam 31 by means of fork 36 and patterning mechanism 38 which may comprise one cam disc of a series of cam discs 39 on the known disc shaft 35 located at the back of the machine to control various operations of the automatic welt-turning apparatus.

We claim:

1. In a straight bar knitting machine of the kind equipped with automatic welt-turning apparatus including a welt bar movable away from the needles during the production of at least a part of the welt fabric and towards them to turn the welt, and with biassed draw-off apparatus for connection to a welt rod; a mechanism for relaxing the pull of the said apparatus during said advance of the welt bar, comprising a rotary draw-off member biassed to rotate in a draw-off direction, a ratchet wheel for transmitting reverse rotation to said member to relax the draw-off pull, a pawl carrier rotatable about the axis of the ratchet wheel, a pawl on the carrier for driving the ratchet wheel, a device for holding the pawl out of engagement with said wheel, means for moving the pawl into engagement with said

wheel upon rotation of the carrier, and means for rotating said carrier to apply reverse rotation to said member at the required time.

5 2. In a machine according to claim 1, a flexible pull connection wrapped round the carrier to rotate it, a bluff for holding the pawl out of engagement with the ratchet wheel until the carrier is rotated by the pull connection, and a part on the pawl engaged under said connection whereby a pull on the connection urges the pawl towards engagement with the ratchet.

10 3. In a Cotton's patent knitting machine equipped with automatic welt-turning apparatus including a welt bar movable away from the needles during the production of at least a part of the welt fabric and towards them to turn the welt, and with biassed draw-off apparatus for connection to a welt rod; a mechanism for relaxing the pull of said apparatus on the welt rod during approach of the welt bar to the needles, comprising a rotary draw-off member for connection to the welt rod, biassing means for biassing it to turn in a draw-off direction, a coupling for rotating it in the reverse direction and for idling during draw-off rotation and comprising a part which is rotatable about an axis during said reverse rotation but is stationary during draw-off rotation of said member, a rotary cam, a cam-operated member movable thereby, a cam follower on the last said member for engaging the cam, pattern-controlled means for bringing the cam and follower into and out of operative register, and a connection between the cam-operated member and the aforesaid part for turning the latter about the said axis to apply the reverse rotation to the draw-off member.
